UNITED STATES PATENT OFFICE.

FRANK C. VANDERGRIFT, OF AKRON, OHIO, ASSIGNOR TO THE WILLIAMS FOUNDRY & MACHINE COMPANY, OF AKRON, OHIO, A CORPORATION OF OHIO.

PLATEN

Application filed October 23, 1924. Serial No. 745,315.

To all whom it may concern:

Be it known that I, FRANK C. VANDERGRIFT, a citizen of the United States, residing at Akron, in the county of Summit and State of Ohio, have invented a certain new and useful Improvement in Platens, of which the following is a full, clear, and exact description, reference being had to the accompanying drawings.

10 This invention relates to platens for power presses, such as are used in the vulcanizing or curing of rubber, and more especially to steel platens as distinguished from the cast iron variety which are used at the present time almost exclusively because of the difficulties heretofore encountered in the manufacture of highly efficient and successful steel platens.

15 The invention also has to do with the method of producing the platen.

As is well known to those familiar with the manufacture of rubber articles, power presses, such as pressure-fluid or hydraulic presses, equipped with a series of platens 25 that are movable toward and from each other between the head and the ram of the press, are used for heating or cooling the molds by placing the molds between the platens, pressing the platens and molds together, and circulating a heating or cooling medium through the platens.

The objects of this invention are:

First, to provide a comparatively thin and correspondingly light platen which is 35 highly efficient, strong and durable and wherein the heating or cooling medium is thoroughly distributed throughout the area of the heat exchanging surfaces;

Second, to provide a platen of the foregoing character that is comparatively simple and cheap of manufacture;

Third, to provide a platen comprised of sections having interengaging parts which interlock in such manner as to very effectively bind the parts together; and

Fourth, to provide a method of producing a platen characterized by the feature last above mentioned.

Further objects, and advantages accruing 50 from my improved construction, will appear as I proceed to describe the invention in detail, reference being had to the accompanying drawings wherein Fig. 1 is a plan view of the platen with a part of the upper section broken away; Fig. 2 is a section on

the line 2-2 of Fig. 1; Figs. 3 and 4 are enlarged sectional details on the respective lines 3-3 and 4-4 of Fig. 1; and Fig. 5 is a transverse section through the separated sections of the platen and illustrates 60 the method of assembly.

While the platen may be made in various shapes best adapted to the purposes for which they are to be used, I have selected as an illustration an annular platen such 65 as may be employed in presses for curing tire beads in either endless ring or spiral bead molds.

The platen is comprised of two sections 70 designated 1 and 2, and these are preferably formed of rolled steel plate and machined to effect on section 1 a peripheral rib 3 and a rib 4 that is spaced inwardly from the former rib a suitable distance and is concentric therewith. It will be noted, especially by reference to the enlarged section, shown in Fig. 3, that the inner sides or edges of these flanges are undercut perceptibly. The section 2 is formed with a rib 5 about 75 its inner edge, a rib 6 that is spaced inwardly a suitable distance from its outer edge, and an intermediate rib 7 which divides the channel or passageway 8 between the ribs 5 and 6 into two circumferential ducts that intercommunicate through cut-away portions or openings 9 in the rib 7. It will be noted that the outer sides or edges of the ribs 5 and 6 are formed complementary to the inner sides or edges of the ribs 3 and 4 so that when the sections are brought 80 together in a manner hereinafter described there is an actual interlocking similar to a dove-tail connection between the engaging ribs of the two sections.

The sections are formed in the original 85 instance of a size to snugly fit together as shown in Figs. 1 to 4, and preparatory to assembling these sections, section 1 is heated sufficiently (to approximately 1000° F.), and is applied to the section 2 while the 100 latter is cold. Upon a subsequent cooling of section 1, it shrinks about the ribs of section 2 and the parts are thus very effectively and securely bound together. In use, the sections are of substantially like temperature 105 at all times and consequently there is no danger of the connection between the sections becoming loose.

To further bind the parts together, and more particularly to insure against leakage, 110

the inner and outer edges of the two sections are welded together as by forming grooves at the joints and filling the same with steel designated 10.

- 5 At a suitable point in its circumference the rib 7 is interrupted by a cut, designated 11, and through this cut between the opposed ends of the rib and spaced a suitable distance therefrom, is a partition 12
 10 which extends transversely of the passageway 8 and interrupts its circumferential continuity. Ports 13 and 14 lead through the side of the platen into the opposite ends of the passageway 8, and are fitted for the
 15 connection of pipes 15 and 16, respectively. Through one of these pipes, 15 for example, heating or cooling fluid, such as steam or water, is conducted to the fluid diffusing space or passageway 8, the same flowing entirely about the passageway and escaping through the other pipe.

The platen is provided with a suitable number of ears 17, having openings 18 through which the guide rods of the press 25 extend, and with notches 19 for the usual spacer bolts, all of which is in accordance with common practice.

Having thus described my invention, what I claim is:—

- 20 1. A platen of the class described comprising two sections enclosing between them a fluid diffusing space having an inlet and an outlet, the sections being formed with integral parts which interlock and bind the sections together, the joint between the edges of the sections being brazed or welded.

- 25 2. A platen of the class described comprising two sections having interlocking peripheral ribs which bind the sections together and enclose, with the body portions of the sections, a fluid diffusing space, said space having an inlet and an outlet, the joint between the edges of the sections being brazed or welded.

- 30 3. A platen of the class described comprising a section having a peripheral rib the inner side whereof converges in a direction away from the body portion of the section, and a second section having a rib which is complementary to the former rib and wherein with said former rib interlocks, the sections enclosing a fluid diffusing space having an inlet and an outlet.

- 35 4. A platen of the class described comprising a section having a rib extending about it, the inner side of said rib being undercut, a second section having a portion embraced by said rib, the surface of said part wherein with the rib engages being formed complementary to the inner side of the rib, the sections enclosing a fluid diffusing space having an inlet and an outlet.

- 40 5. A platen of the class described comprising a plate formed with a rib extending about its edge, the inner side of the rib be-

ing undercut, a second plate having a rib spaced inwardly from its edge and the outer side of which is undercut, the rib of the former plate snugly embracing the rib of the second mentioned plate thereby to bind 70 the plates together, the plates enclosing between them a fluid diffusing space having an inlet and an outlet.

6. A platen of the class described comprising two plates having open centers, one plate having a rib extending about its outer edge and another rib spaced outwardly from its inner edge, the second plate having a rib extending about its inner edge and one spaced inwardly from its outer edge, the inner sides 75 of the ribs of the first mentioned plate converging in a direction away from the body portion of the plate and the outer sides of the ribs of the second mentioned plate being formed complementary to the said inner sides of the former ribs, the ribs of the first mentioned plate snugly embracing those of the second mentioned plate thereby to bind the plates together, the plates enclosing between them a fluid diffusing space having an 80 inlet and an outlet.

7. A platen of the class described comprising two annular plates, the first having a peripheral rib and a rib spaced outwardly a 85 suitable distance from its inner edge, the second plate having a rib extending about its inner edge and another spaced inwardly from its outer edge, one of said plates being formed with an intermediate rib which extends toward the opposed surface of the 90 other plate, the inner sides of the ribs of the first mentioned plate and the outer sides of the ribs of the second mentioned plate being undercut, said ribs of the two plates 95 interengaging to bind the plates together, the outer rib of the second mentioned plate and the inner rib of the first mentioned plate, together with the intermediate body 100 portions of said plates, enclosing a fluid diffusing space, the platen having inlet and 105 outlet ports opening into said space.

8. A platen of the class described comprising two annular plates having ribs extending about their inner and outer edges, the ribs of one plate being designed to embrace 110 those of the other plate and the engaging surface of the ribs of the respective plates being undercut thereby to interlock and bind the plates together, the plates enclosing a fluid diffusing space having an inlet and 115 an outlet.

9. The method of producing a platen of the class described which consists in forming a plate with a rib, and another with a part adapted to be embraced by the rib, heating the first plate to expand it with respect to the second, applying it to the second, and allowing it to cool and thus contract its rib about the aforesaid part of the second plate.

10. The method of producing a platen of the class described, which consists in forming a plate with a rib extending about it, the inner side whereof is undercut, and forming another plate with a part adapted to be embraced by, and which is complementary to, said rib, heating the first plate to expand it with respect to the second, applying it to the second, and allowing it to cool and thus contract its rib about the aforesaid part of the second plate.

11. The method of producing a platen of the class described which consists in forming an annular plate with a peripheral rib and a rib adjacent its inner edge the inner sur-

faces of which ribs converge in a direction away from the body portion of the plate, forming a second annular plate with a rib about its inner edge and another spaced inwardly from its outer edge, the outer surfaces of which ribs diverge in a direction away from the body portion of the plate, heating the first mentioned plate so as to expand it with respect to the second, applying it to the second, and allowing it to cool and contract thereby to interlock its ribs with the ribs of the second plate.

In testimony whereof, I hereunto affix my signature.

FRANK C. VANDERGRIFT.
